United States Patent Office.

FREDERICK BECKER, OF BALTIMORE, MARYLAND.

Design No. 2,614, dated April 16, 1867.

DESIGN FOR A CIGAR BOX.

The Schedule referred to in these Letters Patent and making part of the same.

TO ALL WHOM IT MAY CONCERN:

Be it known that I, FREDERICK BECKER, of the city and county of Baltimore, State of Maryland, have invented a new and ornamental Design for Cigar Boxes; and I declare the following, in connection with the accompanying drawings, to be a description of the same.

The box, including the lid, has six sides, two of which are rhombic, the others rectangular, as represented in the drawings. The shape may be described as a rhombic prism. The rhombic form affords a pleasant variation from the usual rectangular shape, and makes a more attractive and ornamental box for the display of the contents upon shelves, cases, &c., where such articles are set forth with the design to attract the eye.

What I claim as new, and desire to secure by Letters Patent, is—

The design for a cigar box of ornamental configuration, as described and represented.
